UNITED STATES PATENT OFFICE.

WILLIAM B. BOLLES, OF MILWAUKEE, WISCONSIN.

OPERATING MECHANISM FOR EXIT-DOORS.

1,383,974.

Specification of Letters Patent.

Patented July 5, 1921.

Application filed September 30, 1918. Serial No. 256,235.

To all whom it may concern:

Be it known that I, WILLIAM B. BOLLES, a citizen of the United States, residing at Milwaukee, in the county of Milwaukee and 5 State of Wisconsin, have invented a certain new and useful Improvement in Operating Mechanism for Exit-Doors, of which the following is a full, clear, and exact description.

The purpose and object of this invention 10 is to provide a device for use upon doors, more particularly those doors which form exit closures of buildings for public meeting places, theaters, etc., which device is so designed and arranged that the lock operating 15 mechanism for such doors as mentioned, may be easily operated from the inside of the door by contact of any portion of the body of a person with the device of this invention, thus making unnecessary the turning of a 20 knob, or the turning of a key. This is particularly important where in case of a necessary hasty exit, and a crowd surges against the door, the lock operating mechanism will be easily operated to permit the release of 25 the door that it may swing outward and permit exit from the door.

The device of this invention is so constructed that the lock for the door may be operated as usual, that is to say, it may be 30 opened by a pass-key, or by the turning of a knob, and the device of this invention is auxiliary and ancillary to the lock, and in no way interferes with its usual operation.

Generally speaking, the invention may be 35 said to comprise the elements and combinations thereof set forth in the accompanying claims.

Reference should be had to the accompanying drawings forming a part of this specification, in which Figure 1 is a sectional elevation showing a door with a lock mortised 40 therein, and the device of my invention in coöperative position; Fig. 2 is a front elevation of the device; Fig. 3 is a rear elevation with the cover of the casing removed; and Fig. 4 shows in elevation a lock casing 45 and those portions of the lock mechanism which coöperate with the device forming the present invention; Fig. 5 is a rear elevation with the cover removed showing a lock having additional features; Fig. 6 is a side elevation of the showing in Fig. 5 with portions in section; Fig. 7 is a transverse sec-

tion through the central part of Figs. 5 and 6.

Referring to the drawings, 1 indicates a casing which is provided with side walls and end walls. The lower end wall has an opening through which a slidable member 3, later to be referred to, may pass.

The casing at its corner portions is provided with openings such as indicated at 4, which are adapted to receive screws for the purpose of fastening the casing to the door.

The casing is provided with a cover, indicated at 2 in Fig. 1, which cover fits the back of the casing and is held in place by any suitable means. Within the casing there is a wall indicated at 5. This wall forms part of, and projects from a body portion 6, which is provided with a central opening 7. The body portion 6 is preferably, although not necessarily, formed integral with the casing 1. Adjacent the opening in the lower wall of the casing there is 70 a guiding wall 8, which also is formed preferably although not necessarily integral with the casing 1.

The member 3 coöperates with the walls 8 and 5, and as the member 3 is caused to 80 move or reciprocate, the movement of the member 3, is in part guided by the walls 5 and 8.

The end of the member 3 is provided with an extension 3' which enters the opening 7 85 in the part 6, and the projection 3' coöperates with a spring 9 which is within the opening 7, and as the member 3 is moved to the position shown in Fig. 3, the spring 9 is compressed and tends to return the member 90 3 to its original position from which it has been moved.

The walls 5, 5^b and 8 together with the extension 3' of the member 3, all assist in guiding the member 3 to move in a straight 95 line, which is quite essential and necessary in order that there shall be no binding of the projection 3' within the opening 7.

Upon the outside of the casing 1, there is pivoted a lever 10, this lever being pivoted 100 at 11, as indicated in Fig. 1. The lever is provided with a rear extending portion indicated at 10^a. This portion is in part cylindrical and is adapted to extend in the opening 3^b formed in the member 3, the opening 3^b being of just the right size to re-

ceive the member 10^a. The fact that the member 10^a has a rounding surface thereby provides what may be termed a rolling contact with the bottom and top surface of the 5 slot 3^b as the lever 10 is moved.

To the member 3 there is secured a pin or projection 12 which extends outwardly from the casing through a slot 2^a formed in the door below the lock, and the opening 13 is 10 of sufficient extent so that the pin 12 may have the necessary movement imparted to it when the lever 10 is operated.

The lock which is indicated in Fig. 4 comprises the usual casing 15 and the locking bolt 16. This locking bolt may be operated by a key, or by a handle, in any well known manner and no attempt will be made to describe the mechanism of the lock, except that portion of the mechanism which 20 operates with the device of the present invention.

As will be readily understood, the precise construction of the lock has no bearing upon the present invention so long as it has a 25 part which may be contacted and operated by the pin or projection 12.

There is a hooked member 17 which engages with a portion of the latch 16 by which it may be withdrawn, and this member 17 coöperates with a pivoted lever 18, which lever 18 in turn coöperates with a sliding member 19. The sliding member 19 extends adjacent an opening 20 in the lock casing, and when the device of the present 35 invention is mounted upon the door, the member 12 is placed in position to coöperate with the sliding member 19, so that as the member 19 is raised it will cause operation of the lever 18, which in turn will 40 move the lever 17 and so cause the withdrawal of the latch or locking bolt 16.

As before explained, the pin 12 extends, when in proper position, beneath the member 19 of the lock.

45 The showing in Figs. 1 and 3 illustrates the position of the various members of the device when the lever 10 is in depressed position and the spring 7 in its compressed position.

50 Normally the spring 7 moves the member 3 downwardly and the lever 10 outwardly from the position shown in Figs. 1 and 3 respectively, and when the lever 10 is depressed it moves the member 3 against the action of spring 7, which in turn causes the member 12 to be moved against the part 19 of the lock thereby withdrawing the latch 16.

The lever 10 is, as shown more particularly in Fig. 2, a broad flat lever which is 60 easily grasped or conducted by the hand or arm of a person seeking exit, and while the lever 10 may assume the particular construction shown in the drawings, I do not intend to limit the invention to the use of this type 65 of lever, as it will be obvious that other

types of lever may be used, or that a bar extending transversely of the door, such as is very commonly used in devices of this character, may be substituted for the lever 10, bars of this character being so well known in the art that no description is deemed necessary.

The advantages of the construction proposed are its simplicity, and the fact that it may be manufactured at low cost, and in addition, the fact that the parts are not apt to get out of order and will not bind or become disorganized in the operation of the device.

In Figs. 5 to 7 inclusive, I have shown a construction of lock operating device in which the mechanism is so constructed that the pin or projection which operates the lock may be caused to move whether the operating lever in front is depressed or raised.

This is by some considered a desirable feature inasmuch as when necessity requires the use of the device for hasty exit, as when egress from the building is sought because of fire, the persons operating the mechanism may in haste and confusion endeavor to raise the operating lever rather than to depress it. It is, of course, a matter of prime necessity that the operating mechanism be of such construction that it may be quickly operated in order to permit exit and avoid congestion as much as possible.

Referring to Figs. 5 to 7, the casing is represented at 1^a and the back plate for the casing at 2^a.

Within the casing is a sliding member indicated at 3^a. This sliding member is provided with a projecting portion 3^c which enters an opening 7^a formed in the part 6^a, which in the present instance is integral with the casing itself, although whether or not it is integral, is immaterial.

Within the opening 7^a there is a spring 9^a which engages with the portion 3^c of the member 3^a and normally projects the member 3^a to substantially the position shown in Fig. 5.

The under side of the member 3^a is notched out and provided with a recess such as indicated at 3^d. The lower end of the member 3^a is provided with a recess 3^e which accommodates an operating part, as later described, and this recess opens into a larger recess 3^f which also accommodates an operating part as later explained.

Secured to the member 3^a is an extension or pin 12^a which is adapted to coöperate with the movable member 19 forming a part of the locking mechanism as shown in Fig. 4.

The member 3^a is guided in its reciprocation by means of walls 5^c and 5^d, which latter wall in the present instance forms an extension of the part 6^a, also by a wall 8^a, formed, in the present instance, as a part 130

of the casing, and may further be guided by means of a wall 8^c which also forms a stop for the member 3^a . These walls which have just been described, together with the 5 extension 3^e , guide the member 3^a in its reciprocation, so that it moves in a straight line.

From the front wall of the casing there 10 extends a stud 14, and upon this stud there is pivoted at substantially the central portion thereof, a lever 15. This lever at its outer end is provided with projections 15^a and 15^b . The projection 15^a receives a link 16 which at its opposite end coöperates with 15 an extension 17 which is formed upon the part 3^g of the member 3^a . This member 3^g serves not only the purpose of supporting the pin 17^a , but also serves to reinforce the member 3^a adjacent the portions of the member 3^a which are cut away to form the recesses 3^e and 3^f .

Coöperating with the extension 15^b is a link 18. This link at its lower end has an inwardly extending arm 18^a , which arm extends within the opening 3^e in the member 3^a . The link 18 adjacent the lower end thereof is provided with a roller 19 which engages with a wall of the casing 1^a , thus serving to guide the link 18 when it is 30 moved, as later described.

The operating lever 10^b which is pivoted to the casing and extends in front thereof, is provided with a rear extending portion 10^e . This member 10^e is cylindrical in 35 shape and is of such size as to substantially occupy the opening 3^e in the sliding member 3^a , and furthermore, the extension 18^a of the link 18 lies just beneath the part 10^e which has just been described.

40 The operation of the device is as follows: Normally the spring 7^a forces the member 3^a to its downward position so that the lever 10^b is in substantially the position shown in full lines in Fig. 6.

45 If the lever 10^b be depressed, the part 10^e is elevated. This part in turn operating upon the member 3^a causes the same to rise against the action of the spring 7^a , and as the member 3^a is caused to rise, the projection 12^a is raised and coöperates with the 50 part 19 of the lock, thereby causing withdrawal of the latch 16.

Under the conditions of operation as just 55 described, as the member 3^a rises, the link 16 is caused to rise, which in turn causes the lever 15 to be tilted about its pivot, which in turn causes the link 18 to descend, and with it the projection 18^a . The projection 18^a merely descends in the opening 3^e , its 60 movement accomplishing no purpose. At the same time, the movement does not in any way interfere with the operation of the parts as previously described.

65 If the lever 10^b be raised, it will cause the part 10^e to engage with the projection

18^a , and so cause the projection 18^a to be depressed. This in turn causes downward movement of the link 18, which in turn causes the lever 15 to be tilted about its pivot and raises the link 16. This link 16 70 being secured to the projection 17, which is in effect carried by the member 3^a , causes the member 3^a to rise against the action of the spring 7^a , and as the member 3^a is caused to rise, the projection 12^a also is raised 75 into contact with the part 19 of the lock. The depth of the groove 3^f into which the projection 18^a extends, is sufficient to permit the required movement of the various parts described in order to accomplish the 80 desired result.

Having described my invention, I claim:—

1. In a device of the character described, a casing, a member within the casing provided with a recessed opening, a spring in 85 said opening, wall members associated with the casing, a sliding member coöperating with said wall members, said sliding member having a projecting portion which extends into said opening and coöperates with the 90 spring therein, a lever pivoted upon the casing and having operative connection with the sliding member, a lock operating member connected with the sliding member.

2. In combination with a door and locking 95 bolt therefor, of a casing carried upon the door, a member within said casing provided with an opening, a spring within said opening, a sliding member within the casing having an extension which coöperates with the 100 opening in the said member and with the spring therein, guide walls formed in the casing whereby the sliding member is guided to move in a linear direction as it is moved, a lever pivoted upon the casing and having 105 operative connection with the sliding member, the said spring being compressed as the lever is moved, and the said spring serving to return the parts to initial position when the lever is released, and means connecting the said sliding member with the locking bolt.

3. In combination with a door and locking bolt therefor, a casing carried upon the door, a member within said casing provided with 115 an opening, a spring within said opening, a sliding member within the casing, said sliding member having an extension which coöperates with the opening in the aforesaid member and with the spring therein, 120 guiding walls within the casing which coöperate with the sliding member serving to guide the sliding member in a linear direction when the sliding member is moved, a lever pivoted upon said casing and having a portion which coöperates with the sliding member to move the same when the lever is moved, and means connecting the said sliding member with the locking bolt, said means including a pin carried by the sliding 125 130

member and extending from the casing into a suitable opening formed in the door.

4. In combination with a door and locking bolt therefor, a sliding member carried by the door and mounted to slide parallel with the door, means for operatively connecting said member and locking bolt, said sliding member being provided with an opening and a recess adjacent the opening, said sliding member also having a notched out part, a lever pivoted at its central portion and extending through the notched out part of the slideable member, a link coöperating with one end of said pivoted member, said link being attached to the said sliding member, a second link coöperating with the other end of the pivoted lever, said second link being provided with an extension which coöperates with the said recess in the sliding member, an operating lever pivotally mounted upon the door, said operating lever being provided with a part which occupies the opening in the said sliding member and in position to coöperate with the extension upon the said second link.

5. In a device of the character described, the combination with a casing, a sliding member within said casing, means within the casing for guiding the sliding member, said sliding member being provided with an opening and with a recess adjacent the said opening, a lever pivoted adjacent its central portion within the casing, a link connecting one end of said lever with the sliding member, a second link at one end connected with the pivoted member, said link adjacent its opposite end being provided with an extension which lies within the recess in the sliding member, said link also being provided with means which engages a wall of the casing to guide the said second link in its movement, an operating lever pivoted upon the casing and having a part which extends without the casing, said operating lever having a part which coöperates with the opening in the sliding member, and lies adjacent the said extension upon the second link.

6. In a device of the character described, the combination with a casing, a sliding member within said casing, means within the casing for guiding the sliding member,

said sliding member being provided with an opening and with a recess adjacent the said opening, a lever pivoted adjacent its central portion within the casing, a link connecting one end of said lever with the sliding member, a second link at one end connected with the pivoted member, said link adjacent its opposite end being provided with an extension which lies within the recess in the sliding member, said link also being provided with means which engages a wall of the casing to guide the said second link in its movement, an operating lever pivoted upon the casing and having a part which extends without the casing, said operating lever having a part which coöperates with the opening in the sliding member, and lies adjacent the said extension upon the second link, and resilient means for returning the sliding member to initial position after the operating lever has been moved.

7. In a device of the character described, the combination with a casing, a part within said casing having an opening, a spring within said opening, a slideable member within the casing, said slideable member being provided with an extension which coöperates with said opening and the spring therein, said slideable member being provided with an opening and also a recess adjacent the opening, a lever pivoted at its central portion within the casing, a link connecting one end of said lever with the said slideable member, a second link connected with the opposite end of said pivoted lever, means for guiding said second link as it moves, a member extending within the recess formed in the slideable member, said member being connected with the second mentioned link, an operating lever pivoted upon the casing, having a part which extends on the outside of the casing, said operating lever having a part which coöperates with the opening in the slideable member and is positioned adjacent the member extending within the recess of the slideable member for the purpose described.

In testimony whereof I hereunto affix my signature.

WILLIAM B. BOLLES.
